UNITED STATES PATENT OFFICE.

WILLIAM P. ARON, OF DALLAS, TEXAS, ASSIGNOR, BY DIRECT AND MESNE ASSIGNMENTS, TO ARON ELECTRIC RAZOR COMPANY, OF WILMINGTON, DELAWARE, A CORPORATION OF DELAWARE.

ELECTRICAL SAFETY RAZOR.

Application filed January 8, 1926. Serial No. 80,014.

This invention relates to electrical appliances and more particularly to electrically operated razors, the primary object of which is to provide an apparatus of this character 5 adapted to expedite shaving by affording an improved means for imparting a reciprocating movement to the cutting blade of the razor.

It is a further object of the invention to 10 provide a razor of the character designated, having certain features permitting ready removal of parts to facilitate cleaning thereof, and permitting replacement of such parts should they become worn or impaired 15 through use.

It is further the object of the invention to provide a razor of durable and lasting construction having few and simple parts, to enable the instrument to be manufactured at 20 a low cost.

The invention accordingly comprises the elements and combination of elements, features of construction, and arrangements of parts which will be exemplified in the structure hereinafter described, and the scope of the application of which will be indicated in the following claims.

In the accompanying drawings, in which is illustrated one of various possible embodiments of the invention,

Figure 1 is a front elevation of the invention.

Figure 2 is a rear elevation, the handle being depicted in vertical section.

Figure 3 is a perspective view of the invention.

Figure 4 is a perspective view of the shield and blade actuating member.

Figure 5 is a perspective view of the blade actuating member and,

Figure 6 is a perspective view of the preferred form of blade.

Corresponding reference characters indicate corresponding parts throughout the several views of the drawings.

In proceeding in accordance with the foregoing, the invention comprises a hollow handle 1, exteriorly shouldered and threaded at each end. This handle encloses a 50 electromagnetic coil 2, to which suitable electrical current is conveyed through wires 3, connected thereto.

Threaded upon the lower end of the

handle 1, is a cap 21 apertured to receive the leads 3. Across the aperture is a closure 55 disk 22 by which the handle is sealed.

Threaded upon the upper end of the handle 1 is a cap 4, apertured to admit a magnetic pole 5 of the coil 2, and upon the cap, the blade retaining shield or head and 60 blade actuating member are secured. The reference character 6 denotes this shield or head, while the character 7 indicates the blade actuating member.

Particular attention is directed to the construction of the shield 6, as well as its relation to the actuating member 7. The shield is of skeleton construction to enable the same to be readily cleaned after use of the razor, adding materially to the sanitary features 70 thereof, and in addition to this, is of such construction as to obviate the necessity of requiring a cover to envelop the blade, as is usually the case in razors of the safety variety. Particular reference to the blade 75 8, in Figure 6, will disclose that the latter is equipped with an enlargement 9, adapted to be received within a clip 10 forming an integral part of the shield 6, while a longitudinal ridge 11 in the clip 10 as in Figures 80 3 and 4, engages the enlargement 9 of the blade and holds the latter positively from displacement other than that due to longitudinal movement. The enlargement 9 of the blade is provided with slots or apertures 85 12, which, when the blade is in its proper position within the clip 10, registers with a small slot or opening 13 near one end of the clip.

Referring to the blade reciprocating 90 member 7, attention is directed to the detail view thereof shown in Figure 5. This member is shown as being constructed of a yieldable spring having an armature portion 14, and an arm 25 directed upwardly therefrom at an angle to the normal to said blade. The tip of the arm 25 normally engages within one of the slots 12 of the blade 8, thereby locking the blade in the head. It will be observed in Figure 5, that a small 100 offset or shoulder α is formed in the tip of the arm 7, where it enters the slot 12 of the blade. When the leads 3 are connected to a suitable source of alternating current, magnetic induction imparted by the coil 105 through the pole 5 reacts upon the spring

armature 14, when in position upon the cap 4, such action producing intermittent or vibratory movement of the arm 25. The shoulder *a* contacts with the edge of the 5 slot 13 during movement of the arm to reciprocate the blade 8 within the clip 10, in which it has free longitudinal movement, controlled by the position of the arm 25 within the slot 12. The blade moves in 10 shuttle fashion.

In de-blading the instrument, it is required only to force the armature portion 14 of the spring downwardly, thereby disconnecting the arm 25 from the slot 12, 15 whereupon the blade is free to move from its position within the clip 10.

It is therefore obvious that when electrical energy is imparted to the coil 2, such energy is sufficient to react upon the spring 20 armature 14, through the magnet pole 5, to move the arm 25, thereby causing the blade 8 to reciprocate. See Figure 2.

By virtue of the above construction, the blade is positively actuated in both directions through a predetermined stroke by a single moving element, namely, the spring 25 armature 7. Furthermore, the handle 1, in which all of the electrical parts are located, is sealed and has no moving parts therein 30 nor extending therefrom.

In view of the above, it will be seen that the several objects of the invention are achieved and other advantageous results attained.

35 As many changes could be made in carrying out the above constructions without departing from the scope of the invention, it is intended that all matter contained in the above description or shown in the accompanying drawing shall be interpreted as 40 illustrative and not in a limiting sense.

I claim:

1. An electrical razor including a hollow 45 handle and a head, an electromagnetic coil within the handle; a blade mounted for reciprocation parallel to its edge in said head and provided with an aperture; and a spring armature interposed between said blade and said coil and having a portion 50 engageable in the aperture of said blade and adapted, when actuated by the coil, to

reciprocate said blade positively in both directions.

2. An electrical razor including a hollow handle and a head, an electromagnetic coil 55 within the handle; a blade mounted for reciprocation parallel to its edge in said head and provided with an aperture; and a spring armature beneath said head having a portion engageable in the aperture of said blade to lock the same in said head and adapted, when actuated by the coil, to reciprocate said blade positively in both directions; said armature being displaceable to effect release of the blade from said head. 65

3. An electrical razor including a hollow handle and a head; an electromagnetic coil within the handle; a blade mounted for reciprocation parallel to its edge in said head; a spring armature beneath said head having a portion inclined to the normal to said blade and engaging said blade; and a core 70 within said coil and extending through said handle and adapted to cause the armature to reciprocate said blade positively in both 75 directions; said portion releasably locking said blade in said head.

4. An electrical razor including a hollow handle; a head; a blade mounted for reciprocation in said head and provided with 80 an aperture; a spring armature beneath said blade having a portion engageable in the aperture of said blade; and means to attract the spring armature magnetically to move the blade in one direction; the resiliency of said armature causing the blade 85 to move in the reverse direction.

5. An electrical razor including a hollow handle and a head; an electromagnetic coil within the handle; a blade mounted for reciprocation parallel to its edge in said head 90 and provided with an aperture; an armature interposed between said blade and said coil having a portion engageable in the aperture of said blade and adapted, when 95 actuated by the coil, to reciprocate said blade positively in both directions; said armature locking said blade in said head and being adapted, upon displacement from normal position, to release said blade. 100

In testimony whereof I affix my signature.

WILLIAM P. ARON.
